UNITED STATES PATENT OFFICE.

CHARLES DORRITY, OF NORTH WESTERN, NEW YORK.

APPARATUS FOR NAVIGATION OF WATERWAYS.

No. 926,981.

Specification of Letters Patent.

Patented July 6, 1909.

Application filed March 8, 1902. Serial No. 97,265.

To all whom it may concern:

Be it known that I, CHARLES DORRITY, of North Western, in the county of Oneida and State of New York, have invented a certain 5 new and useful Apparatus for Navigation of Waterways, of which the following is a specification.

My invention has for its object the production of an apparatus for the navigation of 10 waterways, which is particularly simple in construction and highly efficient and practical in use; and to this end, it consists in the devices and combinations hereinafter set forth and claimed.

15 Figure 1 is a perspective view of a waterway and boats provided with my apparatus. Fig. 2 is a detail top plan view of a portion of one of the boats and the guiding arm therefor. Fig. 3 is a detail view of a modified construction of said arm and the corresponding track.

It is well known to those skilled in the art that boats passing in canals and other waterways, especially in open country and windy 25 weather, are often turned from their course by the wind, thus frequently occasioning damage to the boats on the banks of the waterways, delaying the boats in transit and subjecting the navigators to more or less danger. 30 My apparatus obviates these difficulties and also furnishes a particularly practical means for propelling the boats by electricity.

This apparatus consists of tracks A A' arranged along the waterway, and means provided on the boats B (shown by dotted lines in Fig. 1) and coöperating with the tracks A A' for guiding the boats. The tracks A A' are supported by a frame a which is of any 40 desirable form, size and construction. The track A is rigid, is arranged in an upright plane on the side of the frame a, and is preferably of sufficient width to permit engagement thereof by the arm b, presently described, irrespective of the amount of water drawn by the boat. If desired, however, said track may be comparatively narrow and the arm for engaging the same may be adjustable vertically as shown in Fig. 3, in which 45 A^o and b^o represent, respectively, a track and an arm of such construction. The track A' is also rigid and is here shown as a rail arranged lengthwise of the frame a above the track A although the relative positions of the tracks A A' is obviously immaterial. In 55 the preferable construction of my apparatus,

I arrange two tracks A A back to back in the center of the waterway and two tracks A' A' directly above the tracks A A, but this arrangement is not an essential feature of my 60 invention, since if two of each of the tracks A A' are used, the same may be supported at the opposite sides of the waterway, and if desired, the waterway may be equipped with only one of each of said tracks. The tracks 65 A A' or the frame a supporting the same form a convenient support for a suitable electric conductor C from which power for driving the boats may be derived when desired.

The means coöperating with the tracks 70 A A' for guiding the boat consists of an arm b projecting laterally from the boat and engaging the track A for limiting the movement of the boat toward the tracks, and guys b' for limiting the movement of the boat 75 from the tracks. Said arm b is movable endwise on the boat between suitable guides b² by an adjusting member b³ and is provided with an antifriction member b⁴ detachably 80 and slidably engaging the track A. I generally use but one arm b on the front end of the boat B, and utilize the ordinary rudder, not illustrated, to control the rear end of the boat, but a boat may be equipped with any desired number of the arms b arranged one in 85 advance of the other. The adjusting member b³ is of any desirable form, size and construction, is held in its adjusted position by any suitable means, unnecessary to describe herein, and is here shown as revoluble, as 90 supported by the boat B and as connected to the arm b by a flexible connection, as a rope b⁵ having its intermediate portion wound around the adjusting member and its ends fixed to the arm b at opposite sides of said adjusting member. The main parts of the guys b' are preferably formed of flexible material so as to give the boat more or less play, and corresponding ends of said guys are detachably secured to the ends of the boat and 100 their other ends are provided with antifriction members b⁶ movable along the track A'. 105

My invention is not limited to any particular means for propelling the boats as clearly seen in Fig. 1, in which at the left-hand I have shown a vessel moving in one direction by steam-power, and at the right-hand a vessel provided with means electrically connected to the conductor C and moving in the opposite direction by electric power. Said 110 invention is also not limited to the exact arrangement of the tracks A A' or the detail

construction of the means for limiting the movement of the boat toward and away from the tracks.

Having thus fully described my invention, 5 what I claim as new and desire to secure by Letters Patent, is:—

1. In an apparatus for navigating waterways, the combination of a boat, a track arranged along the waterway for guiding a 10 boat, an arm associated with the boat and projecting laterally from the same and engaging the track, said arm being adjustable relatively to the boat and to the track and means for adjusting said arm, substantially 15 as and for the purpose described.
2. In an apparatus for navigating waterways, the combination of a boat, a track arranged along the waterway for guiding the boat, an arm projecting laterally from the 20 boat and having its outer end provided with an antifriction member for engaging the track, said arm being movable endwise relatively to the boat, a revoluble adjusting member supported by the boat, and flexible 25 means connected to and movable by the adjusting member and connected to the arm at opposite sides of said adjusting member, substantially as and for the purpose specified.
3. In an apparatus for navigating water-

ways, the combination of a boat, two tracks 30 arranged along the waterway, an arm projecting laterally from the boat and engaging one of the tracks and movable lengthwise thereof, and a guy having one end secured to the boat and the other movable along the 35 other track, substantially as and for the purpose set forth.

4. In an apparatus for navigating waterways, the combination of a boat, means for guiding the boat comprising two tracks arranged along the waterway, an arm projecting laterally from the boat and engaging one of the tracks and movable lengthwise thereof, and a pair of guys having corresponding ends secured to the ends of the boat and their 40 other ends slideable along the other track, substantially as and for the purpose described.

In testimony whereof, I have hereunto signed my name in the presence of two at- 50 testing witnesses, at Syracuse, in the county of Onondaga, in the State of New York, this 6th day of February, 1902.

CHARLES DORRITY.
